CEMENT LASTING MACHINES

John Leslie Lutjens and John William Pratt, Leicester, England, assignors to United Shoe Machinery Corporation, Flemington, N. J., a corporation of New Jersey

Application January 6, 1953, Serial No. 329,842

Claims priority, application Great Britain
January 23, 1952

2 Claims. (Cl. 12—8.8)

This invention relates to end-lasting machines, and is herein illustrated as embodied in a toe-lasting machine constructed in some respects as disclosed in United States Letters Patent No. 2,134,148, granted on October 25, 1938 upon application of W. T. B. Roberts, and as later modified by improved mechanism disclosed in United States Letters Patent No. 2,140,652 granted on December 20, 1938. The machines shown in these patents are especially designed for use on shoes in which the margin of the upper throughout its width is lasted over the insole in generally parallel relation to a last bottom. It will be understood that in many of its novel and useful aspects the present invention is not limited to machines of the illustrated type nor to machines for lasting the toe ends of shoes.

Machine organizations of the character described in the patents just cited employ power operated toe end-embracing wipers for wiping the toe end of an upper first heightwise of the last by relative movement of the wipers and the last and then inwardly over an insole on the last, together with tacking mechanism operative to hold the lasting margin of the upper in over-wiped position. Whereas the machine disclosed in the earlier Roberts Patent No. 2,134,148, has tack nozzles arranged to be positioned for operation close to the inner edges of wipers that have been partially retracted (thereby exposing the portion of the over-wiped margin to be tacked), substantially improved results in lasting are attained, as explained in the subsequently issued patent above mentioned, by providing for the tacking to occur after a repeated inward rather than a refractive wiper movement. It is an object of the present invention to provide a further improved lasting machine retaining the advantages of machines having end-wipers operating substantially in the manner disclosed in this latter Roberts patent, and having, in addition, means capable after the repeat inward wiping movement of effectively end-lasting foot wear with an adhesive, instead of tacks, for fastening the lasting margin and insole.

For more permanent retention of the preliminary shape imparted to an upper by the action of wipers and/or other lasting instrumentalities, and also for the purpose of facilitating subsequent outsole attaching, it has been found desirable to minimize the folds, pleats or bunching inevitably formed in a lasting margin, especially in its toe portion. Such treatment of the margin is likewise recognized as being particularly important in improving the bond between a pre cemented lasting margin and an insole. Accordingly, having the above object in mind, a feature of this invention comprises the combination with end-embracing wipers movable inwardly over an insole on a last and means for causing the wipers, after wiping pre-coated upper materials inwardly, to retract and then again move inwardly to positions nearer the insole edge than at the end of their first inward wiping movement, of mechanism operating in time relation to the wiper movements for applying pressure to substantially all of that portion of the lasting margin of the upper extending inwardly be-

yond the wiping edges of the wipers after their repeat inward wiping movement. It is a further feature of the invention to provide, in a lasting machine of the character just described, means for delivering said pressure with an initial impact to overcome resilience in the rimpled margin of the upper, followed by a sustained compacting pressure and wiper dwell that flattens the arcuately extending marginal portion of the lasted upper material while obtaining the superior bond that is desired.

In the illustrative machine the means employed for applying compacting pressure to that portion of the overlasted margin extending inwardly beyond the wiping edges of the wipers comprises a pair of presser members that is articulated from an open to a closed position in a manner similar to the movements of the wipers. Each presser member is also movable lengthwise and heightwise of the shoe and carries an arcuate work-engaging portion which projects toward the shoe bottom from a flat plate-like portion. The arrangement is such that, the wipers having arrived in the closed position in which they firmly press the lasting margin nearer the insole edge, the presser members are advanced farther lengthwise of the shoe relatively to the closed wipers, the arcuate projecting portions thus being carried across the wiping edges of the wipers and closing to form one continuous rib for engaging substantially the entire inner portion of the overlasted margin. At this time in the cycle of operations a ram-like bar is caused to strike the plate-like portions of the pressure members with considerable impact, the marginal upper material ahead of the wiping edges of the wipers thereby being dealt a flattening blow by the above-mentioned projecting portions which thereafter are urged to apply a sustained compacting pressure.

In order to enable concerted pressure to be applied, by means of the presser ribs and wipers, on the lasting margin for the desired or required period of time, the illustrative machine is provided with operator-controlled clutch mechanism providing for three stopping positions during a complete operating cycle. The clutch mechanisms of the machines disclosed in the Roberts patents mentioned above enable an operator to trip the clutch to start a cycle and to trip it again after the first over-wipe of the wipers when he is satisfied that a shoe is being correctly lasted. These two stopping positions are retained, though relatively timed somewhat differently in the cycle of the illustrative machine, as are its other operating instrumentalities, and in addition, provision is made for a time dwell in which the wipers and presser members are permitted jointly to compress the entire overlasted margin. After the initial portion of this dwell during which the above mentioned hammer blow has been struck against the presser members, the ribs of the presser members are forced with sustained pressure against the inner portion of the toe-lasting margin, the operator tripping the clutch a third time to complete the cycle when the cement has had sufficient time to secure the upper to the insole. It will be understood that a machine embodying the present invention may be driven through any suitable clutch and controlled by starting and stopping mechanism other than that herein disclosed. Moreover, though not herein so disclosed, it will be appreciated that a suitable timing device may be constructed and arranged to trip clutch mechanism automatically after a predetermined minimum time interval of pressure application thus causing the cement lasting machine itself to release the lasted shoe and be reset for the next operating cycle.

The above and other features of the invention, including various novel details of construction and combinations of parts, will now be more particularly described with reference to the accompanying drawings in

Fig. 1 is a view in right-hand side elevation of a machine in which the present invention is embodied; a portion being broken away to show a detail of internal construction;

Fig. 2 shows in right-hand side elevation, on an enlarged scale as compared with Fig. 1, the wiper operating mechanism of the machine, this view being in large measure like Fig. 4 of the Patent No. 2,140,652 above mentioned;

Fig. 3 is a view mainly in right-hand side elevation of the auxiliary plates with projecting ribs and mechanism for controlling striking pressure to be exerted thereon;

Fig. 4 is a view in front elevation of a portion of the structure shown in Fig. 3;

Fig. 5 is an enlarged detail, partly in section, of certain parts seen in Fig. 3;

Fig. 6 is a perspective view, on an enlarged scale, of the operating parts of the machine as positioned at the start of a cycle;

Fig. 7 is a perspective of portions of the clutch mechanism of the machine, as seen from the rear, and shown partially in Fig. 1;

Fig. 8 is a view in side elevation with portions being shown in section of the clutch operating mechanism;

Fig. 9 is a section showing one presser member in operative relation with the wipers on the overlasted margin of a shoe.

Since the illustrative cement lasting machine, both in construction and operation, largely resembles the improved tack toe lasting machine disclosed in the previously-mentioned Letters Patent when tacking mechanism is omitted, portions common to both types of machine are hereinafter only briefly described unless a more complete treatment is considered helpful to better comprehension of the invention as embodied in the exemplary machine.

For wiping the toe end of the upper heightwise of the last and for wiping its margin inwardly over an insole on the last, the machine to which the invention is herein shown as applied is provided with a pair of toe embracing wipers 10 (Figs. 2, 6 and 9) which operate on a last positioned bottom upward. Their manner of operation relatively to the last is fully set forth in the abovementioned Letters Patent No. 2,140,652 and is such that they are, after retraction, for a second time lowered to press firmly on the lasting margin and again receive a closing movement to complete the wiping operation with their wiping edges not so far from the edge of the insole as at the end of their first wiping movement. Operative on the overwiped lasting margin in time relation to the wipers 10 is a pair of auxiliary presser members generally designated 12 (Fig. 6) hereinafter further described. The machine also comprises a frame 13 supporting a jack-carrying shaft 14 (Fig. 1) on which is mounted an upwardly extending casting 16 slidably carrying a jack post 18 provided at its upper end with means for supporting a shoe. The jack is swung rearwardly into a vertical position indicated in Fig. 2 to present the shoe with its toe end in predetermined relation to the wipers 10, and a treadle 20 (Fig. 1) is then depressed to elevate the post 18 and thus carry the bottom of the forepart of the shoe against a holdown (not herein shown) for determining the position of the shoe heightwise, the holdown determining a parallel relation between the shoe bottom and the wipers 10 and later acting to depress the shoe at a certain time in the lasting operation. For supporting the toe end of the shoe under the holdown a detachable toe rest 22 (Figs. 1 and 9) is provided and a heel end support generally designated 24 is arranged to support the shoe on the post 18 so that the toe end face will contact or be spaced a predetermined small amount from a compressible toe end gage 26.

Like the machine more fully disclosed in Letters Patent No. 2,140,652, the machine herein shown is provided with

fingers 28 (Fig. 6) mounted for cooperative clamping action with the wipers 10 in spreading and tensioning the lasting margin of the upper. The movements of these fingers throughout a cycle are substantially as described in United States Letters Patents No. 2,138,308, granted on November 29, 1938, upon another application of W. T. B. Roberts. It will be understood that in the present machine the fingers 28 are moved, upon withdrawal from over the wipers, to a lower position beyond the wipers to afford clearance for operation of the presser members 12 on the overwiped lasting margin.

The wipers 10 are respectively mounted on wiper carriers 30 (Fig. 2) which are supported, through brackets 32, on a pair of castings 34 movable vertically along rods 38, 38 (only one shown) and on other parallel fixed rods 40, the parts associated primarily with only one of the wipers being visible in the drawings. For moving the wipers heightwise of a last, as hitherto disclosed, the castings 34 have their respective lower ends connected by a link 42, 20 (one only shown), to a lever 44 mounted on a rod 46 and connected by a link 48 to a lever 50 which carries a roll 52 lying in a cam track 54 formed in a cam wheel mounted on a main cam shaft 56 (Figs. 1 and 2). To advance and retract the wipers 10 lengthwise of the last, the brackets 32 are operated by means of links 58 through upwardly extending arms of a lever 60. This lever is operated through a link 62 by a lever 64 (Fig. 2) having a lower connection with a cam (not shown) mounted on the shaft 56. For closing the wipers laterally of the shoe, each of the wiper carriers 30 has connected to it by a ball joint at 66 (Fig. 2) the forward end of a rearwardly extending rod itself connected by ball joint to upwardly extending arms of a lever 68 which is connected through a rod 70 to a lever 72 operated by a cam on the shaft 56. After the wipers have wiped the margin of the upper inwardly over the insole, have retracted, and then again advanced and closed partially to wipe the margin inwardly, means, not herein shown, but operatively connected to the shaft 56 as hitherto disclosed in the Patent No. 2,140,652, are actuated and have connection with the ends of a flexible band 74 (Fig. 6) to cause it to clamp the upper to the last around the toe exteriorly of the shoe bottom. As above indicated, the presser members 12 (corresponding in relative location and operation to the bar of tacker nozzle, positioning plates designated 283 in the Patent 2,134,148) are spaced above the wipers 10 and are advanced and closed in paths similar to the paths of movement of the wipers, the advancing and closing movements being imparted to the members 12 by the same means imparting corresponding movements to the wipers. The members 12 are respectively secured to carriers 80 that are supported in a readily detachable manner on a table 82 (Fig. 6) which is supported at each side by a pair of depending parallel links 84, 85 pivoted at their lower ends to the table. For reasons later explained the construction being described differs from that of the last-mentioned patent in that, as best shown in Fig. 5, the lower ends of the forward links 84 are respectively threaded to receive a member 86 having a slot 88 extending heightwise. Pins 90, affixed horizontally to the table 82, respectively extend through the slots 88 and afford a lost motion connection between the table and the links 85. It will be understood that the presser members 12 are opened or closed laterally of the shoe as they are moved bodily lengthwise by the table 82. The carriers 80 have connected to them by ball joints the forward ends of links 92 which are connected at their rearward ends to depending levers 94 (Figs. 2 and 3). The levers 94 are mounted to swing at their upper ends about a rod 96 in a head casting of the machine and are arranged to be connected at their lower ends to the upper ends of the upwardly extending arms of the lever 68 which impart to the wipers their closing movements. The table 82 which supports the carriers 80 is coupled to the forward ends of links 98 which are connected at their rearward ends to two depending levers 100 mounted on

the rod 96. For the purpose of moving the members 12 lengthwise of the shoe relatively to the wipers 10 during the second inward wiping movement of the latter, so that arcuate depending ribs 102 respectively projecting from the members 12 are safely carried inwardly across the wiping edges of the wipers as they come to rest, each link 92 and 98 is made in two parts serving in toggle devices. This toggle arrangement is fully described in the Patent No. 2,134,148, it being sufficient for present purposes to note that the relative advance movement of the ribs 102 is accomplished by the straightening of the toggle devices when a lever 104 pivoted on a rod 106 is swung downwardly by a cam on a secondary cam shaft 108 (Figs. 1 and 3), the lever 104 having an arm carrying a roll 110 which lies in the track formed in said cam. The shaft 108 is driven through suitable gearing by the main cam shaft 56.

The respective presser members 12 comprise an arcuate, flat upper portion 112 with which the ribs 102 are integral. In their closed position the members 12 (Fig. 6) have their portions 112 and the ribs 102 in a substantially continuous U-shaped configuration, the ribs 102 having flat undersurfaces adapted to press downwardly on the overwiped inner margin of the upper and being shaped to correspond in curvature with the wiping edges of the adjacent wipers 10. The ribs 102 project downwardly from the plate-like portions 112 an amount only slightly greater than the thickness of the wipers 10. For the purpose of avoiding possible confusion due to similarity in appearance it is observed that Fig. 3 somewhat resembles Fig. 9 of the Patent No. 2,134,148 in that where the bottoms of the tacker arms 257 are shown in that Fig. 9 there is correspondingly shown in Fig. 3 herein the presser ribs designated 102.

Means for applying pressure to the members 12 to cause the ribs 102 to flatten, compact, and secure the inner pre cemented margin of the upper lying beyond the closed wipers 10 is herein shown as supported by a head casting 114 (Fig. 1) bolted on the upper face of the machine frame 13. The casting 114 has formed in its front face a vertical guideway for a tubular slide 116 which is connected by a pair of links 118 (Figs. 1, 3 and 4) to a forwardly extending bifurcated portion of a lever 120 movable about a transverse shaft 122 by a cam mounted on the shaft 108. The links 84 are pivotally connected at their upper ends to the lower ends of the links 118, and the links 85 are pivotally connected at their upper ends to the slide 116. Thus the table 82 and the members 12 move upwardly and downwardly as well as lengthwise of the shoe. A driver bar 124 (corresponding to, but longer than, the bar designated 267 in the Patent No. 2,134,148) is mounted for vertical sliding movement in the tubular slide 116 and has at its lower end a U-shaped head 126. Springs 128 (Fig. 4) mounted within the tubular slide 116 are arranged at a certain time to impart rapid downward movement to the bar 124 to cause the head 126 to strike the members 12 simultaneously a hammer blow. The driver bar 124 is operatively coupled normally at its upper end to a crosshead 130 which is connected by a pair of links 132 to a bifurcated portion of a forwardly extending lever 134 mounted on a shaft 136 (Figs. 1 and 4) in the head casting and provided with a cam roll arranged to be operated by a cam on the shaft 108. Accordingly, by movement of the lever 134 the crosshead 130 and the bar 124 connected therewith are raised against the resistance of the springs 128 to compress them preparatory to application of downward pressure on the members 12.

By mechanism now to be described, upon upward movement of the crosshead 130 to raise the bar 124, the latter is held with the springs 128 under compression until that time in the machine cycle when the members 12 and the wipers 10 have closed and occupy the relative

positions shown in Fig. 9. The coupling between the bar 124 and the crosshead 130 (Figs. 3 and 4) comprises a member 140 movable forwardly and rearwardly on guide rolls 142 on the crosshead. A spring 144 normally urges the member 140 forwardly and causes a beveled face 146 thereon to engage an undersurface of a roll 148 on the bar 124. A spring pressed latch 150 pivoted on the member 140 has a hooked forward end which normally engages a plate 152 fastened on the bar 124 and thereby prevents rearward movement of the member 140. The bar 124 is accordingly raised by the upward movement of the crosshead and it is held in raised position with the springs 128 compressed until, during downward movement of the slide 116, the latch 150 is engaged and operated by a latch tripping member 154 so that the member 140 is released to permit it to be moved rearwardly by the roll 148 as the bar 124 is impelled downwardly by the springs 128. The member 154 is threaded to receive a clamping bolt 156 extending through a slot formed in an arm 158 fixedly mounted on gibs 160 (Figs. 1 and 4) which assist in guiding the slide 116. For adjusting the time of release of the bar 124 to downward movement the member 154 is adjusted heightwise by a screw 162 threaded into the arm 158, the head of the screw being partially fitted into a slot in the member 154.

As above indicated, the illustrated machine is started and stopped by clutch mechanism which, in addition to starting a cycle and providing for stopping the machine after the first overwipe of the wipers 10, causes the driver bar 124 to come to rest after a flat undersurface 164 of the head 126 has engaged the portion 112 with impact and thereafter continues to force the ribs 102 against the inner portion of the lasting margin with pressure. Referring to Fig. 1 the main cam shaft 56 has mounted thereon a clutch operating cam 166 having a peripheral track the underside of which is engaged by a cam roll 168 carried by the forward arm of a lever 170 (Figs. 1 and 7). The latter is pivotally mounted on a pin 172 supported by the frame 13 and has a rearward arm pivotally carrying a trip 174 (Fig. 8) that is urged forwardly by a spring plunger 176. A spring 178 maintains the roll 168 in contact with the cam 166. When in its normal forward position the trip 174 engages a notch formed in the lower end of a slide 180 (Figs. 7 and 8) mounted for vertical movement in a bracket 182 affixed to the frame 13. The slide 180 is urged downwardly by a spring 184 and is retained in the bracket 182 by covers 186, 188 bolted thereon. Rocking of the lever 170 as effected by the cam 166 is accordingly effective, through the trip 174, to move the slide 180 against resistance of the spring 184 and thereby rock a three-armed lever 190 pivotally supported by the frame 13, the lever carrying a block 191 accommodated by a horizontal slideway formed in the slide 180. Pivotal movement of the lever 190 controls operation of the machine by means comprising conventional clutch and brake mechanism mounted on a power shaft 192 (Fig. 1). By suitable intermediate gearing (not shown) the shaft 192 is arranged to drive the main cam shaft 56.

The power shaft 192 is housed by a portion of the frame 13 as indicated in Fig. 7 and carries at one end a brake drum 194. When rocked in a clockwise direction (as viewed in Fig. 7) by any one of three high points designated A, B and C on the cam 166 (Fig. 1), the lever 190 acts through a rod 196 to apply a brake strap 198 to the drum 194 and hence a brake to the drive shaft 192. The lever 190 also acts at this time axially to shift a link 200 to release a pulley 202 from frictional driving relation with a clutch 204 mounted on the other end of the power shaft 192 and operation of the machine is thus quickly stopped. The pulley 202 is belt driven and largely covered by a guard 206, and the shaft 192

may be turned over by a hand wheel 208 (Fig. 1) if desired. In order to release the brake mechanism and restore the pulley and clutch to driving relation, the trip 174 is moved rearwardly (i. e. moved clockwise as seen in Fig. 8) against the resistance of the plunger 176 by means of pressure exerted on a knee pad 210 (Fig. 1) carried on the forward end of a rod 212. The latter is connected to one end of a lever 214 affixed to a shaft 216 mounted in bearing brackets secured to the frame 13 and the bracket 182. The other end of the shaft 216 carries a lever 218 (Fig. 8) which pivotally supports an arm 220 engageable endwise with the trip 174. Thus, in starting the machine the operator moves the pad 210 so that the trip 174 is displaced from the notch in the slide 180 by the arm 220 and the slide is thereupon moved downwardly under the influence of the spring 184, the lever 190 consequently being effective to release the brake strap 198 from the drum 194 and finally shift the clutch 204 into driving relation with the pulley 202. A spring plunger 222 mounted in the lever 218 bears on the arm 220 allowing it to yield upon being engaged by the slide 180. Upon releasing the pad 210 a return spring 224 (Fig. 1) mounted on the rod 212 is effective to retract it and the arm 220. The power shaft 192 drives the main cam shaft 56 until the next low portion of the peripheral track of the cam 166 allows the roll 168 to rise under the influence of the spring 178. When the roll 168 is thus raised, the trip 174, due to the plunger 176, is again positioned for engagement with the notch on the slide 180 and will raise this slide to stop the machine when the next high point of the cam 166 depresses the roll 168. Repeat operation of the pad 210 restarts the machine after each high point A, B or C has brought the machine to a stop. In the illustrative arrangement the point A (at approximately 184°) on the cam 166 is effective automatically to stop the machine when the wipers 10 have fully closed to complete their first inward wiping movement over the lasting margin; the point B (at approximately 260°) is effective to stop the machine with the wipers 10 again partially advanced and closed and now pressing on the outer portion of the lasting margin while the driver bar 124 continues to exert downward pressure on the ribs 102 as they bear on the more inward portions of the lasting margin; the point C (at 0° or 360°) stops the machine at the end of the cycle, the shoe then being released from the wipers and presser members 12 which have returned to their starting positions along with the other operating instrumentalities.

Operation of the machine will now be briefly summarized. The shoe being in the operating position shown in Fig. 2 and assuming the operator is satisfied with the lasting condition after the wipers 10 have initially advanced and fully closed to wipe the lasting margin of the upper inwardly over the toe portion of the insole I (Fig. 9), he momentarily presses the pad 210 a second time to cause the power shaft 192 to be driven through the clutch 204 and thereby revolves the cam shaft 56 for that portion of the cycle in which the periphery of the cam 166 from A to B contacts the roll 168. In this portion of the cycle the wipers 10 complete their retractive movement and then again advance to positions in which the wiping edges of the wipers are nearer the edge of the insole than at the termination of their first inward wiping movement. This repeat inward wiping and closing movement of the wipers 10 is effected when they have been lowered to cause them again to apply firm pressure on the pre-cemented margin of the upper. The presser members 12, selected to complement the curvature of the pair of wipers being employed, are moved lengthwise of the shoe and relatively to the wipers 10 by the toggle devices comprising the two-part links 92, 98 and the ribs 102 accordingly slide over the wipers to inward positions for engagement with that portion of the margin lying beyond the wiper

edges as seen in Fig. 9. The slots 88 (Fig. 5) permit the table 82 and hence the carriers 80 and presser members 12 to move vertically somewhat relatively to the links 84. Thus the links 84 will descend slightly after the ribs 102 have engaged the wipers 10, and the slots 88 will allow the members 12 to be depressed relatively to the links 84 so that the ribs 102 may thereafter compress the inner portion of the margin against the insole I. Before the roll 168 is depressed at B to stop the machine the cam shaft 108 has acted via the lever 120 and the links 118 to lower the slide 116 and thus the presser members 12 onto the insole. As the slide 116 is moved downwardly the latch tripping member 154 operates on the latch 150 to release the compressed springs 128. The driving bar 124 is consequently forcibly impelled downward, its head 126 striking the portions 112 just above the ribs 102 and causing the latter to press the pre-cemented inner marginal portions of the upper against the insole. The ribs 102 thus act to flatten those inner marginal portions likely to have been more rumpled and pleated during the lasting operation and will, as the machine is automatically stopped by the point B of the cam 166, continue under the influence of the springs 128 to press and compact such marginal portions thereby permitting the wipers 10 independently to dwell with more effective pressure on the lasting margin nearer the insole edge.

The action of the two independently acting pressing means, i. e., of the ribs and the wipers, succeeds during the dwell in holding the entire pre-cemented and overlasted margin flatter and in closer relation to the insole while the cement is setting than if wipers alone were to be suddenly forced against an entire overwiped margin at the toe end. While it is true that that portion of the lasting margin of the upper operated on by the ribs may later be trimmed away as surplus, nevertheless on those critical marginal portions of the upper which are to remain in the finished shoe near the edge of the shoe bottom, the wipers can, because of the compacting effected by the ribs, concentrate their pressure and obtain a smoothly lasted toe. As soon as the shoe has remained under pressure of the wipers 10 and the ribs 102 for the time required properly to secure the lasting margin to the insole I, the pad 210 will again be moved to start the machine and cause the cam 166 to revolve from point B to point C relatively to the roll 168. In this final portion of the operating cycle the lasted shoe is released from the machine and the operating instrumentalities are returned to their respective starting positions.

Having thus described our invention, what we claim as new and desire to secure by Letters Patent of the United States is:

1. In a lasting machine having wipers for embracing the upper of a shoe about an end of a last and for wiping, retracting, and then partially rewiping the cemented marginal portion of the upper inwardly over an insole on the last while applying substantial pressure to the upper against the insole, presser members constructed and arranged to be moved heightwise and lengthwise of the shoe, power means for articulating the wipers and presser members widthwise and lengthwise of the shoe bottom to position said members in contiguous relation to the wiping edges of the wipers when the latter assume positions at the end of their pressurized rewiping movement, and a spring-impelled hammer for forcing the presser members when so positioned into compacting engagement with that portion of the margin of the upper lying inwardly beyond the wiping edges of the wipers.

2. In a lasting machine of the type having wipers for embracing the upper of a shoe about the toe end of a last and for wiping and then partially rewiping the cemented marginal portion of the upper inwardly over

an insole on the last, power means for so moving the wipers, means for causing said wipers to dwell after their rewiping movement in compacting engagement with that portion of the cemented margin of the upper adjacent to the insole edge, and pressing means for independently compacting that portion of the cemented lasting margin extending inwardly beyond the wiper edges, said pressing means being arranged for movement toward operative position by said power means while the latter is effecting the rewiping movement of said wipers.
